Ser. No. 557,608

9 Claims. (Cl. 260—397.3)

ABSTRACT OF THE DISCLOSURE

The disclosure herein relates to fusidic acid derivatives. 15
The compounds claimed herein are useful in the treatment
in such conditions as bursitis.

This application is a continuation-in-part application of 20
U.S. application, Ser. No. 406,877, filed Oct. 27, 1964,
now abandoned.

This invention relates to and has as its object the provision
of new physiologically active steroids, methods for
their production and novel intermediates useful in the
preparation thereof.

More particularly, this invention relates to the production
of steroids of the general formulae

and

wherein R is hydrogen; R' is selected from the group
consisting of hydroxy and acyloxy; and taken together R
and R' is oxo (O=).

The preferred acyloxy radicals are those of hydrocarbon
carboxylic acids of less than twelve carbon atoms, as
exemplified by the lower alkanoic acids (e.g., acetic,
propionic, butyric and tert-pentanoic acid), the lower
alkenoic acids, the monocyclic aryl carboxylic acids (e.g.,
benzoic and toluic acid), the monocyclic aryl lower alka-
noic acids (e.g., phenacetic and β -phenylpropionic acid),
the cycloalkane carboxylic acids and the cycloalkene car-
boxylic acids.

The final products of this invention are physiologically
active and may be employed in combination with such
solvents a dimethyl sulfoxide or tetrahydrothiophene-1,1-
dioxide in the treatment of such conditions as bursitis and
rheumatoid arthritis, the concentration and/or dosage being
adjusted for the relative potency of the compound
employed.

The final products of this invention may be prepared
by the process of this invention which entails a number of
steps beginning with methyl fusidate as starting material.
The steps of the process of this invention may be repre-

2

sented by the following equations wherein R, R', R'' and
R''' may represent hydrogen, alkyl, acyl or oxo (O=):

65 In the first step of this invention, methyl fusidate is
acylated as by treatment with an acid anhydride, for

example, acetic anhydride, to yield the 3,11-diacyloxy derivative thereof, a new compound of this invention.

[In this application and in the appended claims, whenever in the formulae set forth herein line (f) is employed in the linkage of atoms, it is meant to denote that the connected atom may be either in the alpha or beta position, for example, in Compounds E the 18 β epimer may be treated with an alkali metal base, for example, potassium hydroxide to yield the 18 α derivative.]

The 3,11-diacyloxy derivative of methyl fusidate is then first ozonized and then reduced to yield a mixture of Compounds B, C and D, which are also new compounds of this invention.

Compounds C and D may then be hydrogenated to yield the saturated Compound E. Hydrolysis of Compounds C and D gives Compounds F and D (R=H), respectively.

Compounds F and D (R=H) may then be oxidized as by treatment with an oxidizing agent, for example, chromium trioxide to yield the 3-keto derivatives which are new final products of this invention.

Compounds F may then be hydrogenated as by treatment with hydrogen in the presence of a palladium catalyst to yield the saturated 3-keto derivatives (Compounds E) which are also new final products of this invention.

Alternatively, the compounds of this invention may be prepared from the intermediate having the formula

R²=acyl as defined hereinabove, which is a product recovered when the 3,11-diacyl derivative of methyl fusidate is oxidized and then reduced. This product may then further be reduced utilizing reflux temperatures to yield compounds B, C and D of this invention.

Compound B of the instant invention may be hydrogenated to yield its corresponding saturated product having the formula

The invention may be illustrated by the following examples:

Example 1.—Methyl fusidate 3,11-diacetate

Forty grams of methyl fusidate are added to a solution of 40 g. of p-toluenesulfonic acid and 80 ml. of acetic anhydride in 160 ml. of acetic acid and the mixture left at room temperature for twenty minutes. The solution is then carefully diluted with ice while stirring, then diluted with water and extracted with chloroform. The chloroform is then washed several times with water and evaporated to dryness in vacuo, to give 46 g. of crude methyl fusidate 3,11-diacetate.

Similarly, if propionic anhydride or butyryl anhydride are substituted for acetic anhydride, the dipropionate and dibutyrate are obtained, respectively.

Example 2.—4 α ,8,14-trimethyl - 18 - nor- Δ^{12} -5 α ,8 α ,14 β -androstene-3 α -ol-17-one 3-acetate, 4 α ,8,14-trimethyl-

18 - nor - $\Delta^{12,15}$ -5 α ,8 α ,9 β ,14 β - androstadiene-3 α -ol-17-one 3-acetate and 4 α ,8,14-trimethyl-18-nor- Δ^{15} -5 α ,8 α ,9 β ,13 β ,14 β -androstene - 3 α ,11 α - diol - 17 - one 3,11-diacetate

5 A solution of 6 g. of methyl fusidate 3,11-diacetate in a mixture of 122 ml. of methylene chloride and 1.22 ml. of pyridine is cooled in an acetone-Dry Ice bath and 443 liters of ozonized oxygen (1.1 mmoles O₃ per liter) are slowly passed through. Twelve milliliters of acetic acid and 6 g. of zinc dust are then added and the mixture stirred vigorously at room temperature for ninety minutes. It is then filtered and washed with chloroform. The combined filtrate and washings are then extracted successively with water, 5% sodium bicarbonate and water, dried over anhydrous magnesium sulfate and evaporated to dryness, in vacuo. The residue is then redissolved in 500 ml. of acetic acid, 11 g. of zinc dust is added and the mixture refluxed for four hours. It is then filtered, diluted with water and extracted with chloroform. The chloroform is washed well with water and then evaporated to dryness, in vacuo. The residue is dissolved in chloroform:hexane (1:1, v.v.) and plate chromatographed using Woelm neutral alumina (Activity V) as adsorbent and chloroform-hexane (1:1, v.v.) as developing solvent. The band detectable by U.V. at Rf 0.3-0.7 eluted by ethyl acetate evaporated to dryness and crystallized from acetone-hexane to give 663 mg. of 4 α ,8,14-trimethyl-18-nor- Δ^{12} -5 α ,8 α ,9 β ,14 β -androstene - 3 α - ol-17-one 3-acetate having a melting point about 138-140°;

30 $[\alpha]_D^{22} - 262^\circ$ (chl.), $\lambda_{\text{max}}^{\text{vis}}$ 245 m μ (ϵ , 9500), $\lambda_{\text{max}}^{\text{Nujol}}$ 5.82, 5.88, 610 μ

35 τ 33.37 (m., 12-H), 5.09 (m., 3 β -H), 7.93 (s., 3-acetate), 8.83 (s., methyl), 8.95 (s., methyl), 8.98 (s., methyl), 9.15 (d., J=6,4-methyl).

Analysis.—Calc'd for C₂₃H₃₄O₃ (358.50): C, 77.05; H, 9.56. Found: C, 77.39; H, 9.29.

The band detectable by U.V. which had an Rf=0.2 is eluted with ethyl acetate and the residue after removal of the solvent on crystallization from acetone-hexane gives 20 mg. of 4 α ,8,14-trimethyl-18-nor- Δ^{15} -5 α ,8 α ,9 β ,13 β ,14 β -androstene-3 α ,11 α -diol-17-one 3,11-diacetate having a melting point of about 215-217°,

40 45 $[\alpha]_D^{24} - 82^\circ$ (chl.), $\lambda_{\text{max}}^{\text{vis}}$ 226 m μ (ϵ , 8400), $\lambda_{\text{max}}^{\text{Nujol}}$ 5.80 5.90, 6.30 μ

45 τ 2.60 (e., J=6, 15-H), 3.92 (d., J=6, 16-H), 4.87 (m., 11 β -H), 5.10 (m., 3 β -H), 8.00 (s., 3,11-diacetate), 8.78 (s., methyl), 8.88 (s., methyl), 8.92 (s., methyl), 9.17 (d., J=6, 4-methyl).

50 Analysis.—Calc'd for C₂₅H₃₆O₅ (416.54): C, 72.08; H, 8.71. Found: C, 72.33; H, 8.15.

55 By re-plate chromatographing of the mother liquors from the 4 α ,8,14-trimethyl-18-nor- Δ^{12} -5 α ,8 α ,9 β ,14 β -androstene-3 α -ol-17-one 3-acetate several times a second U.V. detectable band is evident which is slightly more polar than the above compound. Crystallization of the material obtained from this band from acetone-hexane gives 60 mg. of 4 α ,8,14-trimethyl-18-nor- $\Delta^{12,15}$ -5 α ,8 α ,9 β ,14 β -androstadiene-3 α -ol-17-one 3-acetate having a melting point about 173-175°,

60 $[\alpha]_D^{24} - 47^\circ$ (chl.), $\lambda_{\text{max}}^{\text{vis}}$ 248 m μ (ϵ , 9300), $\lambda_{\text{max}}^{\text{Nujol}}$ 5.81, 5.95, 6.08, 6.30 μ

65 τ 2.51 (d., J=6, 15-H), 3.50 (m., 12-H), 3.81 (d., J=6, 16-H), 5.08 (m., 3 β -H), 8.80 (s., methyl), 8.93 (s., methyl), 9.14 (d., J=5, 4-methyl), 9.19 (s., methyl).

70 Analysis.—Calc'd for C₂₃H₃₂O₃ (356.47): C, 77.49; H, 9.95. Found: C, 77.42; H, 9.13.

Example 3.—4 α ,8,14-trimethyl-18-nor-5 α ,8 α ,9 β ,13 β ,14 β -androstane-3 α ,ol-17-one 3-acetate

To a solution of 400 mg. of 4 α ,8,14-trimethyl-18-nor- Δ^{12} -5 α ,8 α ,9 β ,14 β -androstene-3 α -ol-17-one 3-acetate in 56

ml. of absolute ethanol 400 mg. of 5% palladium on calcium carbonate are added and the stirred mixture hydrogenated at room temperature for sixteen hours. The mixture is filtered and evaporated to dryness in vacuo. Crystallization of the residue from acetone-hexane gives 331 mg. of $4\alpha,8,14$ -trimethyl-18-nor-5 $\alpha,8\alpha,9\beta,13\beta,14\beta$ -androstane-3 α -ol-17-one having a melting point about 143-145°,

$$[\alpha]_D^{22} + 18^\circ \text{ (chl.f.), } \lambda_{\text{max}}^{\text{Nujol}} 5.78\mu$$

τ 5.05 (m., 3 β -H) 7.96 (s., 3-acetate), 8.71 (s., methyl), 9.06 (s., methyl) 9.10 (s., methyl) and 9.17 (d., J=6, 4-methyl).

Analysis.—Calc'd for $C_{23}H_{36}O_3$ (360.52): C, 76.62; H, 10.07. Found: C, 76.63; H, 9.82.

Example 4.— $4\alpha,8,14$ -trimethyl-18-nor-5 $\alpha,8\alpha,9\beta,13\beta,14\beta$ -androstane-3 α -ol-17-one 3-acetate

Following the procedure of Example 3, but substituting $4\alpha,8,14$ -trimethyl-18-nor- $\Delta^{12,15}$ -5 $\alpha,8\alpha,9\beta,14\beta$ -androstadiene-3 α -ol-17-one 3-acetate for the $4\alpha,8,14$ -trimethyl-18-nor- $\Delta^{12,15}$ -5 $\alpha,8\alpha,9\beta,14\beta$ -androstadiene-3 α -ol-17-one 3-acetate, there is obtained the desired product.

Example 5.— $4\alpha,8,14$ -trimethyl-18-nor- $\Delta^{12,15}$ -5 $\alpha,8\alpha,9\beta,14\beta$ -androstadiene-3 α -ol-17-one

A solution of 107 mg. of $4\alpha,8,14$ -trimethyl-18-nor- $\Delta^{12,15}$ -5 $\alpha,8\alpha,9\beta,14\beta$ -androstadiene-3 α -ol-17-one 3-acetate in 10 ml. of 1 N potassium hydroxide in 95% ethanol is blanketed with helium and left at room temperature for sixteen hours. The solution is then neutralized with 2 N hydrochloric acid diluted with water and extracted with chloroform. The chloroform is washed with water and evaporated to dryness, in vacuo. Crystallization of the residue from acetone-hexane gives 75 mg. of $4\alpha,8,14$ -trimethyl-18-nor- $\Delta^{12,15}$ -5 $\alpha,8\alpha,9\beta,14\beta$ -androstadiene-3 α -ol-17-one having a melting point about 184-186°,

$$[\alpha]_D^{23} - 23^\circ \text{ (chl.f.), } \lambda_{\text{max}}^{\text{Nujol}} 249 \text{ m}\mu \text{ (}\epsilon, 7500\text{), } \lambda_{\text{max}}^{\text{Nujol}} 2.90, 5.95, 6.08, 6.30\mu$$

τ 2.56 (d., J=6, 15-H), 3.54 (m., 12-H), 3.92 (d., J=6, 16-H), 6.28 (m., 3 β -H), 8.83 (s., methyl), 8.96 (s., methyl), 9.06 (d., J=6, 4-methyl), 9.22 (s., methyl).

Example 6.— $4\alpha,8,14$ -trimethyl-18-nor- $\Delta^{12,15}$ -5 $\alpha,8\alpha,9\beta,14\beta$ -androstene-3 α -ol-17-one

Following the procedure of Example 5, but substituting $4\alpha,8,14$ -trimethyl-18-nor- $\Delta^{12,15}$ -5 $\alpha,8\alpha,9\beta,14\beta$ -androstene-3 α -ol-17-one 3-acetate for $4\alpha,8,14$ -trimethyl-18-nor- $\Delta^{12,15}$ -5 $\alpha,8\alpha,9\beta,14\beta$ -androstadiene-3 α -ol-17-one 3-acetate, there is obtained $4\alpha,8,14$ -trimethyl-18-nor- $\Delta^{12,15}$ -5 $\alpha,8\alpha,9\beta,14\beta$ -androstene-3 α -ol-17-one.

Example 7.— $4\alpha,8,14$ -trimethyl-18-nor- $\Delta^{12,15}$ -5 $\alpha,8\alpha,9\beta,14\beta$ -androstadiene-3,17-dione

To a solution of 50 mg. of $4\alpha,8,14$ -trimethyl-18-nor- $\Delta^{12,15}$ -5 $\alpha,8\alpha,9\beta,14\beta$ -androstadiene-3 α -ol-17-one in 2 ml. of reagent grade acetone a solution containing 20 mg./ml. of chromic anhydride and 32 mg./ml. of sulfuric acid in acetone-water (9:1, v.v.) is added dropwise until the oxidizing agent is no longer decolorized. After five minutes the excess oxidizing agent is decomposed with methanol and on careful dilution with water crystals separate. These are filtered, washed with water and dried. Recrystallization from acetone-hexane gives 41 mg. of $4\alpha,8,14$ -trimethyl-18-nor- $\Delta^{12,15}$ -5 $\alpha,8\alpha,9\beta,14\beta$ -androstadiene-3,17-dione having melting point about 174-176°,

$$\lambda_{\text{max}}^{\text{Nujol}} 247 \text{ m}\mu \text{ (}\epsilon, 9200\text{), } [\alpha]_D^{25} + 15^\circ \text{ (chl.f.), } \lambda_{\text{max}}^{\text{Nujol}} 5.90, 6.02, 6.30\mu$$

τ 2.54 (d., J=6, 15-H), 3.54 (m., 12-H), 3.88 (d., J=6, 16-H), 8.72 (s., methyl), 8.77 (s., methyl), 8.97 (d., J=6, 4-methyl), 9.23 (s., methyl).

Analysis.—Calc'd for $C_{21}H_{32}O_2$ (312.44): C, 80.73; H, 9.03. Found: C, 80.78; H, 9.00.

Example 8.— $4\alpha,8,14$ -trimethyl-18-nor- $\Delta^{12,15}$ -5 $\alpha,8\alpha,9\beta,14\beta$ -androstene-3,17-dione

Following the procedures of Example 7, but substituting $4\alpha,8,14$ -trimethyl-18-nor- $\Delta^{12,15}$ -5 $\alpha,8\alpha,9\beta,14\beta$ -androstadiene-3 α -ol-17-one for the $4\alpha,8,14$ -trimethyl-18-nor- $\Delta^{12,15}$ -5 $\alpha,8\alpha,9\beta,14\beta$ -androstadiene-3,17-dione having a melting point about 153-155°,

$$[\alpha]_D^{22} - 219^\circ \text{ (chl.f.), } \lambda_{\text{max}}^{\text{Nujol}} 246 \text{ m}\mu \text{ (}\epsilon, 8300\text{), } \lambda_{\text{max}}^{\text{Nujol}} 5.88,$$

10 6.04

τ 3.38 (m., 12-H), 8.73 (s., methyl), 8.80 (s., methyl), 8.97 (d., J=6, 4-methyl), 9.05 (s., methyl).

Analysis.—Calc'd for $C_{21}H_{30}O_2$ (314.45): C, 80.21; H, 9.62. Found: C, 80.15; H, 9.66.

Example 9.— $4\alpha,8,14$ -trimethyl-18-nor-5 $\alpha,8\alpha,9\beta,13\beta,14\beta$ -androstane-3 α -ol-17-one

Hydrogenation of $4\alpha,8,14$ -trimethyl-18-nor- $\Delta^{12,15}$ -5 $\alpha,8\alpha,9\beta,14\beta$ -androstene-3 α -ol-17-one as described in Example 3 gives $4\alpha,8,14$ -trimethyl-18-nor-5 $\alpha,8\alpha,9\beta,13\beta,14\beta$ -androstane-3 α -ol-17-one having a melting point about 159-161°;

$$[\alpha]_D^{24} + 46^\circ \text{ (chl.f.), } \lambda_{\text{max}}^{\text{Nujol}} 2.90, 5.82$$

25 6.27 (m., 3-H), 8.72 (s., methyl), 9.08 (s., methyl), 9.10 (d., J=6, 4-methyl), 9.11 (s., methyl).

Analysis.—Calc'd for $C_{21}H_{34}$ (318.48): C, 79.199; H, 10.76. Found: C, 79.18; H, 10.81.

30 Example 10.— $4\alpha,8,14$ -trimethyl-18-nor-5 $\alpha,8\alpha,9\beta,13\alpha,14\beta$ -androstane-3 α -ol-17-one

A solution of 100 mg. of $4\alpha,8,14$ -trimethyl-18-nor-5 $\alpha,8\alpha,9\beta,13\beta,14\beta$ -androstane-3 α -ol-17-one 3-acetate in 10 ml. of 1 N potassium hydroxide in 95% ethanol is kept at room temperature under helium for sixteen hours. It is then neutralized with 10% acetic acid diluted with water and extracted with chloroform. The chloroform extracts are washed with water and evaporated to dryness, in 40 vacuo.

Plate chromatography of the residue using Woelm neutral alumina (Activity V) as adsorbent and chloroform as the developing solvent gave two bands detectable by iodine vapor at Rf 0.6 and 0.4, respectively. Elution of the less polar band with ethyl acetate and crystallization of the residue from acetone-hexane after removal of the solvent gives 11 mg. of $4\alpha,8,14$ -trimethyl-18-nor-5 $\alpha,8\alpha,9\beta,13\alpha,14\beta$ -androstane-3 α -ol-17-one having a melting point about 215-217°,

$$[\alpha]_D^{24} - 56^\circ \text{ (chl.f.), } \lambda_{\text{max}}^{\text{Nujol}} 2.80, 5.88\mu$$

45 τ 6.23 (m., 3-H), 8.76 (s., methyl), 9.07 (d., J=6, 4-methyl), 9.11 (s., methyl), 9.13 (s., methyl).

Analysis.—Calc'd for $C_{21}H_{34}O_2$ (318.48): C, 79.19; H, 10.76. Found: C, 79.16; H, 10.63.

50 Example 11.— $4\alpha,8,14$ -trimethyl-18-nor-5 $\alpha,8\alpha,9\beta,13\beta,14\beta$ -androstane-3,17-dione

Oxidation of $4\alpha,8,14$ -trimethyl-18-nor-5 $\alpha,8\alpha,9\beta,13\beta,14\beta$ -androstane-3 α -ol-17-one following the procedure as described in Example 7 gives $4\alpha,8,14$ -trimethyl-18-nor-5 $\alpha,8\alpha,9\beta,13\beta,14\beta$ -androstane-3,17-dione having a melting point about 182-184°,

$$[\alpha]_D + 117^\circ \text{ (chl.f.), } \lambda_{\text{max}}^{\text{Nujol}} 5.77, 5.80\mu$$

55 τ 8.68 (s., methyl), 8.93 (s., methyl), 8.98 (d., J=6, 4-methyl), 9.13 (s., methyl).

Analysis.—Calc'd for $C_{21}H_{32}O_2$ (316.47): C, 79.70; H, 10.19. Found: C, 79.79; H, 10.14.

60 Example 12.— $4\alpha,8,14$ -trimethyl-18-nor-5 $\alpha,8\alpha,9\beta,13\beta,14\beta$ -androstane-3,20-dione

Following the procedure of Example 3, but substituting $4\alpha,8,14$ -trimethyl-18-nor-5 $\alpha,8\alpha,9\beta,13\beta,14\beta$ -androstane-3,17-dione for the $4\alpha,8,14$ -trimethyl-18-nor-5 $\alpha,8\alpha,9\beta,13\beta,14\beta$ -androstane-3,20-dione

14 β -androstene-3 α -ol-17-one 3-acetate, there is obtained the desired product.

Example 13.—4 α ,8,14-trimethyl-18-nor- $\Delta^{12,15}$ -5 α ,8 α ,9 β ,14 β androstadiene-3 α -ol-17-one

A solution of 4 α ,8,14-trimethyl-18-nor- $\Delta^{12,15}$ -5 α ,8 α ,9 β ,14 β androstadiene-3 α -ol-17-one 3-acetate in 5% methanolic KOH and water is refluxed under nitrogen for seven and one-half hours. The solution is then acidified with glacial acetic acid and the resulting solution concentrated in vacuo. Water is added and after cooling the resulting crystals are removed by filtration, to yield the desired product.

Example 14.—3 α ,11 α ,16 β -triacetoxy-4 α ,8,14-trimethyl-18-nor-5 α ,8 α ,9 β ,13 α ,14 β -androstan-17-one

A solution of 6 g. of methyl fusidate 3,11-diacetate in a mixture of 122 ml. of methylene chloride and 1.22 ml. of pyridine is cooled in an acetone-Dry Ice bath and 443 liters of ozonized oxygen (1.1 mmoles O₃ liter) and slowly passed through. Twelve milliliters of acetic acid and 6 g. of zinc dust are then added and the mixture stirred vigorously at room temperature for ninety minutes. It is then filtered and washed with chloroform. The combined filtrate and washings are then extracted successively with water, 5% sodium bicarbonate and water, dried over anhydrous sodium sulfate and evaporated, in vacuo. Plate chromatography of the residue on neutral alumina (Activity V) gave one elution with chloroform 3 α ,11 α ,16 β -triacetoxy-4 α ,8,14-trimethyl-18-nor-5 α ,8 α ,9 β ,13 α ,14 β -androstane-17-one having a melting point about 149-151°,

$\lambda_{\text{max}}^{\text{Nujol}}$ 5.74, 5.84 μ ; $\tau_{\text{CDCl}_3}^{\text{Si(Me)}}$ 4.72

(m., H—C—OAc), 5.10 (m., H—C—OAc), 7.86 (s., OAc), 7.92 (s., OAc), 7.98 (s., OAc), 8.50 (s., —CH₃), 9.01 (s., —CH₃), 9.03 (s., —CH₃), 9.15 d., J=6, 4 α -CH₃), $[\alpha]_D^{22}$ —104° (chloroform).

Example 15.—4 α ,8,14-trimethyl-18-nor-5 α ,8 α ,8 β ,14 β -androst-12-ene-3 α -ol-17-one-3-acetate; 4 α ,8,14-trimethyl-18-nor-5 α ,8 α ,9 β ,14 β -androst-12,15-diene-3 α -ol-17-one-3-acetate and 4 α ,8,14-trimethyl-18-nor-5 α ,8 α ,9 β ,13 β ,14 β -androst-15-ene-3 α ,11 α -diol-17-one-3,12-diacetate

By refluxing 3 α ,11 α ,16 β -triacetoxy-4 α ,8,14-trimethyl-18-nor-5 α ,8 α ,9 β ,13 α ,14 β -androstan-17-one with zinc dust in acetic acid as described in Example 2, the above compounds are obtained.

Example 16.—3 α ,11 α -diacetoxy-4 α ,8,14-trimethyl-18-nor-5 α ,8 α ,9 β ,14 α -androstan-17-one

A solution of 25 mg. of 3 α ,11 α -diacetoxy-4 α ,8,14-trimethyl-18-nor-5 α ,8 α ,9 β ,14 β -androst-15-ene-17-one in 5 ml. of absolute ethanol is hydrogenated at room temperature and atmospheric pressure using 25 mg. of 5% palladium or calcium carbonate as catalyst. The mixture is then filtered, evaporated and the residue crystallized from acetone-hexane to give 23 mg. of 3 α ,11 α -diacetoxy-4 α ,8,14-trimethyl-18-nor-5 α ,8 α ,9 β ,14 β -androstan-17-one having a melting point about 186-188°, $[\alpha]_{600}$ —114°, $[\alpha]_{500}$ —95°, $[\alpha]_{400}$ —76°, $[\alpha]_{350}$ $\pm$ 0°, $[\alpha]_{330}$ +48°, $[\alpha]_{305}$ +80°, $[\alpha]_{293}$ $\pm$ 0° (in methanol).

Analysis.—Calc'd for C₂₅H₃₈O₅ (418.55): C, 71.74; H, 9.15. Found: C, 71.87; H, 9.00.

The invention may be variously otherwise embodied within the scope of the appended claims.

What is claimed is:

1. A compound selected from the group consisting of steroids of the formulae

wherein R' is hydrogen; R'' is selected from the group consisting of hydroxy and acyloxy; wherein the acyl radical is of a hydrocarbon carboxylic acid of less than twelve carbon atoms; and together R' and R'' is oxo (O=).

2. A compound of the formula

wherein R' and R'' are as defined in claim 1.

3. A compound having the formula

40 wherein R² is acyl and R' is as defined in claim 1.

4. A compound in accordance with claim 2 having the name 4 α ,8,14-trimethyl-18-nor- $\Delta^{12,15}$ -5 α ,8 α ,9 β ,14 β -androstadiene-3-17-dione.

5. A compound in accordance with claim 1 having the name 4 α ,8,14-trimethyl-18-nor- Δ^{12} -5 α ,8 α ,9 β ,14 β -androstene-3 α -ol-17-one.

6. A compound in accordance with claim 1 having the name 4 α ,8,14-trimethyl-18-nor-5 α ,8 α ,9 β ,13 β ,14 β -androstane-3 α -ol-17-one-3-acetate.

7. A compound in accordance with claim 1 having the name 4 α ,8,14-trimethyl-18-nor-5 α ,8 α ,9 β ,13 α ,14 β -androstane-3 α -ol-17-one.

8. A compound in accordance with claim 1 having the name 4 α ,8,14-trimethyl-18-nor-5 α ,8 α ,9 β ,13 β ,14 β -androstane-3,17-dione.

9. A compound in accordance with claim 3 having the name 3 α ,11 α ,16 β -triacetoxy-4 α ,8,14-trimethyl-18-nor-5 α ,8 α ,9 β ,13 α ,14 β -androstan-17-one.

UNITED STATES PATENT OFFICE
CERTIFICATE OF CORRECTION

Patent No. 3,376,324

April 2, 1968

Patrick A. Diassi

It is certified that error appears in the above identified patent and that said Letters Patent are hereby corrected as shown below:

Column 2, last formula at the bottom of the column should be labeled -- G --. Column 3, line 38, "heerinabove" should read -- hereinabove --; lines 46 to 56, the upper right-hand portion of the formula should appear as shown below:

line 74, "5 α ,8 α ,14 β " should read -- 5 α ,8 α ,9 β ,14 β --. Column 4, line 26, "ehtyl" should read -- ethyl --; line 33, "33.37" should read -- 3.37 --; line 69, "0.95" should read -- 9.05 --. Column 6, line 28, "79.199" should read -- 79.19 --; line 69, "19.14" should read -- 10.14 --. Column 7, lines 3 and 5, "nor-12,15", each occurrence, should read -- nor-12,15, --; line 19, "0₃ liter" should read -- 0₃ per liter --; line 28, "one" should read -- on --; line 39, "8 β " should read -- 9 β --; line 53, "ene" should read -- en --.

Signed and sealed this 2nd day of December 1969.
